REFLECTING SIGN CONSTRUCTION

Charles A. Persons, Worcester, Mass., assignor to
 Persons-Majestic Manufacturing Company,
 Worcester, Mass., a corporation of Massachusetts

Application August 26, 1938, Serial No. 226,973

9 Claims. (Cl. 40—130)

The present invention relates to improvements in reflecting signs of the general type shown by United States Letters Patent to MacDonald et al., No. 1,914,142, granted June 13, 1933.

- 5 In said MacDonald et al. patent, each individual autocollimator or reflector button has a cylindrical sheet metal casing that provides a protective closure for the reflecting surface and a portion of the lens; a portion of this casing, inwardly of an annual flange or shoulder thereon, has pressed or otherwise formed therein an external screwthread, said threaded portion being adapted to pass through one of a series of button-receiving apertures formed in the front plate or 10 panel of the sign, and arranged in the usual manner to delineate the desired warning, signal, word, letter, or other symbol. The flange on said casing is of larger diameter than said opening, and seats against the outer surface of the front 15 plate or panel of the sign; the button is positioned by screwing onto the inner threaded portion of said casing an internally threaded cup member, whose rim engages the inner surface of the plate or panel around said opening in opposition to 20 said flange's engagement of the outer surface around said opening.

Heretofore, this method of mounting and holding reflector buttons in a sign has not proved practical; in certain instances, where vibrations, 25 due to traffic, have been heavy and frequent, the screw-thread engagement between button casing and cup has loosened up, allowing the buttons to shift or tip into positions wherein their light-reflecting properties are materially reduced; 30 in many other instances, with buttons so mounted, malicious persons and pilferers, by manipulating them from the front of the sign, have been able to unscrew them from their cups and to remove them bodily from the sign.

35 The primary object of the present invention is to overcome, in reflecting button mountings of this character, the difficulties and disadvantages above mentioned; other and further objects and advantages of the invention will be made apparent in the following detailed description thereof—reference being had in this connection to the accompanying drawings, wherein

40 Fig. 1 is a front elevation of a sign or the like, equipped with reflector button mountings according to my invention.

45 Fig. 2 is a fragmentary large scale view, partly in section and partly in elevation, of the sign shown in Fig. 1.

50 Fig. 3 is a view, partly in section and partly in elevation, illustrating my invention as applied to

a slightly different type of reflecting unit or autocollimator assembly.

Fig. 4, 5 and 6 are views similar to Fig. 3, showing various modifications of my invention.

5 Figs. 7 and 8 respectively are vertical and horizontal sectional views illustrating a further modification of my invention.

Like reference characters refer to like parts in the different figures.

The sign shown in Figs. 1 and 2 employs in 10 conventional manner a back plate A and a front plate B, the latter being provided with button-receiving apertures arranged to delineate the desired word or symbol. After the reflector units have been assembled in and secured, according to my invention, to said apertured front plate B, the two plates A and B are united in any suitable manner, so as to exclude any access to the space C between said plates wherein are disposed the inner threaded portions of the several 15 reflector buttons. For preventing in a completed sign any unauthorized separation of the plates A and B, I may employ, as shown, clamping means D that only can be manipulated by a special tool, or if desired, a padlock may be used to hold 20 the plates together.

In the accompanying drawings, I have illustrated my invention in connection with two different types of button reflectors or autocollimating devices, one type being that shown by Figs. 30 2, 4 and 5, wherein the lens itself on its convex rear face provides the reflecting surface, and the other type being that shown by Figs. 3 and 6, wherein the lens is separated from the reflecting surface by an air space.

35 In each of the reflector units shown by Figs. 2, 4 and 5, I employ a button lens 1 having convex front and rear faces 2 and 3, respectively. Said rear face 3 receives a suitable opaque coating 4 which serves in a manner well known as an 40 effective reflector of light rays passing through the lens, and this dispenses with the necessity of using in the unit a reflector element separate from the lens itself. In each of the units of Figs. 3 and 6, I have shown a button lens 1a or 1b, with 45 which is associated a separate reflecting element 5, the latter being of shallow cup form, with its concave surface suitably plated and burnished, and held in spaced relation to the convex inner surface of lens by engagement of its rim with a 50 flanged shoulder 6 of said lens. In both types of units, the protective housings or encasing means for the lens and the reflecting surfaces have substantially the same characteristics, as follows:

I provide for each of the units of Figs. 2, 4 and 5, a suitable housing in the form, preferably, of a cup-shaped sheet-metal stamping 7 whose cylindrical portion, adjacent the rim thereof, is suitably expanded to provide an external annular flange 8, with the rim material, beyond said flange 8, spun or otherwise turned inwardly to engage snugly in substantially sealing contact an annular flange 9 of the inserted lens 1. The integral bottom 10 of housing 7 is preferably curved to provide a seat for the rear convex mirrored surface 3 of said lens. In the slightly different unit of Fig. 3, the housing 7 has the same external flange 8 and the same spun-over rim engagement with the flange 9 of lens 1a, but the integral bottom 10 of said housing in this case provides a seat for the reflection element 5. In the unit shown by Fig. 6, employing a lens 1b having an external bead or enlargement 11, the housing 7' has to be somewhat longer; its annular flange 8 is spaced by the width of bead 11 from the spun-over rim 9' engaging the outer portion of said bead.

In all cases however, the housing's cylindrical wall, inwardly of the projecting annular flange 8, has pressed or otherwise formed therein suitable corrugations 12 in the form substantially of an external screw-thread—it being understood that this threaded portion of each housing is small enough in diameter to enter freely any of the apertures of the front plate or panel B, but that in every case the housing flange 8 provides a stop or abutment, larger in diameter than such aperture, for engagement with the outer or exposed face of panel B, to limit the inward movement of each unit in the act of assembling and mounting said units on said front panel. Such assembly and mounting, in a secure and tamper-proof fashion, is obtained according to my invention by providing for cooperation with the threaded inner housing portion 12 of each unit a cup-like member 13, whose cylindrical wall is internally formed in any suitable manner with corrugations or threads corresponding to the external corrugations or threads 12 of said housing. This member 13 has its rim flanged outwardly, as shown at 14, to provide a stop or abutment for engagement with the inner face of panel B around the opening therein, in opposed relation to the engagement of the outer face of said panel B by the flange 8. This clamping opposition of the flanges 8 and 14, by which to position and hold each unit in the apertured panel B, is obtained by screwing the internally threaded member 13 onto each reflector housing 7 or 7', after insertion of same in the panel aperture. But in a sign having reflector units so assembled and held, not only can this screw-threaded engagement become loosened by vibration, but also, despite the fact that the space C containing the several members 13, 13 is rendered entirely inaccessible by the attachment of the back plate A, it is still possible for any malicious person, by manipulation of the exposed portions of the reflector units at the front of the sign, to unscrew such units from their retaining members 13, 13.

According to my invention, these difficulties are overcome by the employment of means arranged to prevent any relative turning movement in an unscrewing direction between the housing 7 or 7' and the retaining members 13, 13 thereof. As shown in Figs. 2 and 3, the space between the bottom 10 of housing 7 and the bottom of member 13 is arranged to receive a resilient member 15, here shown in the form of a split or helical lock

washer. The latter is so proportioned as to be put under considerable pressure by the contraction of such space incident to screwing on of member 13 far enough to engage its flange 14 with the inner surface of panel B; consequently, by reason of the very heavy friction obtained by this compression of member 15, (be it lock washer, or spring, as shown in Figs. 2, 3, 4 and 7 or rubber washer) as shown in Figs. 5 and 6, it is impossible to produce by turning movement imparted to the exposed portion of a unit at the front of the sign any relative rotation in an unscrewing direction between said unit's housing and the screwed-on member 13; instead, if any such turning can be made to take place, the member 13, by reason of such increased friction, will invariably turn in unison with the button housing 7. The resilient member 15 can be made with a large enough diameter to have a snug fit with the interior of member 13, thus avoiding separation of the two parts in ordinary handling. Or if desired, as shown in Figs. 7 and 8, the bottom of cup member 13 may have struck up from same a bendable retaining tongue 16, folded back on the resilient member 15 to hold the latter in place within said cup member. It is of advantage also to roughen the opposed bottom surfaces of housing 7 and cup member 13, as shown at 20, Figs. 5 and 6, in the areas thereof engaged by the interposed resilient member 15.

Instead of using a separate resilient member 15, the cup member 13 itself may be made of material suitable for tempering, and the bottom of this member, may be formed with struck-up integral prongs 17, 17, adapted when the member is screwed up tight, to bite into the softer metal of the casing 7; this construction is illustrated in Fig. 4.

I claim:

1. In a reflecting sign construction, a panel 40 having button-receiving apertures, reflector buttons each insertible in one of said apertures, each button comprising a casing for a lens and a reflecting surface, said casing being flanged at its front portion to engage the front side of the panel 45 around the associated aperture and threaded at its rear portion projecting through said aperture, an internally threaded member cooperating with said threaded casing portion to hold each button in said panel, said member being flanged at its 50 rim to engage the rear side of the panel around the associated aperture and a resilient device adapted to be compressed between said member and said casing when the flanged portions are in clamping engagement with opposite sides of said 55 panel.

2. A two-piece reflector button mounting adapted to cooperate with a panel provided with a button-receiving aperture, said mounting comprising an inner shell containing a lens and a reflecting surface and formed with threads and an outwardly projecting rim, an outer shell formed with cooperating threads and a rim, said outwardly projecting rim adapted to limit the rearward movement of said inner shell through said aperture, the rim of said outer shell adapted to limit the forward movement of said mounting through said aperture when said outer shell is screwed onto said inner shell and spring means adapted to engage frictionally with both of said shells when their rims are in clamping engagement with the panel, thereby to resist rotation which would screw said outer shell off said inner shell.

3. In a sign, the combination with a plate pro- 75

vided with an aperture, of a light-reflecting element and a holder for same comprising two bodies having screw threaded engagement with each other, said bodies having clamping abutments 5 on opposite sides, respectively, of said plate about said aperture, spring means adapted to be compressed by said bodies and to permit free relative rotation between them only in the direction which would screw said abutments into clamping 10 engagement with said plate.

4. In a sign, the combination with a light-reflecting element, said element comprising a light-transmitting lens and a reflector associated with and disposed behind said lens, of a mounting 15 for said element comprising two bodies, one of which has an inwardly directed seat for said reflector, said bodies having screw-threaded engagement with each other and having outwardly directed clamping abutments, a plate provided 20 with an aperture whose margin is clamped between said abutments and spring means adapted to be compressed by said bodies and to resist rotation which would release said compression.

5. In a sign, a light-reflecting element and a 25 mounting for said element, said element comprising a light-transmitting lens and a reflector associated with and disposed behind said lens, said mounting comprising two bodies one of which has a seat for said reflector, said bodies having screw-threaded engagement with each other and having clamping abutments, a plate provided with an aperture whose margin is clamped between 30 said abutments and spring means adapted to be compressed by said bodies and to permit free rotation of said bodies in only one direction.

6. In a sign, the combination with light-reflecting means comprising a lens and a reflecting surface, of a mounting for said reflecting means, comprising two bodies, one of which provides the 35 inclosure for said light reflecting means, said bodies having screw-threaded engagement with each other and having outwardly directed clamping abutments, a plate provided with an aperture whose margin is clamped between said abut- 40 ments and a spring adapted to be compressed by

said bodies and to resist rotation which would release said compression.

7. In a sign, a light reflecting means and a mounting therefor, said light reflecting means comprising a lens and a reflecting surface, and said mounting comprising two bodies, one of which encases said light-reflecting means, said bodies having screw-threaded engagement with each other and having clamping abutments, a plate provided with an aperture whose margin is 10 clamped between said abutments and compressible means interposed between said bodies and put under compression by the relative movement between them which disposes their abutments in clamping relation to said plate. 15

8. In a sign, a light reflecting means and a mounting therefor, said light reflecting means comprising a lens and a reflecting surface, said mounting comprising two bodies, one of which encases said light-reflecting means, said bodies having screw-threaded engagement with each other and having clamping abutments, a plate provided with an aperture whose margin is 20 clamped between said abutments and compressible means interposed between said bodies and 25 put under compression by the relative movement between them which disposes their abutments in clamping relation to said plate, the surfaces of said bodies being roughened in the areas thereof contacted by said interposed compressible means. 30

9. In a sign, the combination with light-reflecting means comprising a lens and a reflecting surface, of a mounting for said reflecting means, comprising two bodies, one of which provides the inclosure for said light reflecting means, said bodies having screw-threaded engagement with each other and having outwardly directed clamping abutments, a plate provided with an aperture whose margin is clamped between said abutments, a spring adapted to be compressed by said bodies 35 and to resist rotation which would release said compression and means integral with one of said bodies for preventing separation of said spring from said body. 40

CHARLES A. PERSONS. 45
